UNITED STATES PATENT OFFICE.

GUSTAVUS A. PADDOCK, OF BEAVERDAM, WISCONSIN.

HARVESTER-REEL.

SPECIFICATION forming part of Letters Patent No. 685,004, dated October 22, 1901.

Application filed April 3, 1899. Serial No. 711,473. (No model.)

To all whom it may concern:

Be it known that I, GUSTAVUS A. PADDOCK, a citizen of the United States, residing at Beaverdam, in the county of Dodge and State 5 of Wisconsin, have invented certain new and useful Improvements in Harvester-Reels, of which the following is a specification.

The object of my invention is to provide a neat, smoothly-running, and durable reel 10 wherein the beaters shall move swiftly when first entering the grain and slowly when leaving it. This object is gained by the construction illustrated in the accompanying drawings, in which—

15 Figure 1 is a view of the reel as seen when standing at the grain end of the sickle-bar; Fig. 2, a sectional view of the reel and its supporting-standard and driving mechanism as seen from the front, and Fig. 3 is a view 20 of the inner ends of the reel-arms and connections in an upright position and of the guide lying horizontally and embracing a section of the flange of the cam-plate. Fig. 4 is an end view of the inner ends of the reel-arms 25 with their connections and an outside view of the guide in an upright position with a section of the flange of the cam-plate.

L is a standard for supporting the reel and is hinged by the gudgeon M to the frame of 30 the machine, its relative position being shown by the guard N. Vertically movable on this is the sleeve-frame H, said frame being provided at its upper part with a bearing for the vertical drive-shaft K. To the opposite end 35 of the sleeve-frame is secured a circular cam-plate G, with an annular flange g. In the front part of the sleeve-frame and also in the cam-plate are bearings for the reel-shaft A, to one end of which is secured the bevel gear-wheel I. The bevel-pinion J, which meshes 40 with said gear-wheel, rests in the bearings in the sleeve-frame and with it is vertically movable on the drive-shaft K and is supplied with a key which fits into and slides in a groove 45 in said shaft, which, like the standard L, is hinged to the harvester-frame at its lower part. The means of holding the standard L and sleeve-frame H in position are common in the art, and therefore do not need to be 50 shown here.

The reel-head has four radial arms b coming out at right angles to the reel-shaft A next

to the cam-plate, and four others, b', standing at an angle at the other end, the outer ends of these furnishing bearings in which pivots 55 formed of the rods c oscillate. Triangular bearing-plates formed of castings E rest upon the rods c. The lugs i, i', and h, are fitted to the rods, and the reel arms are secured outside the castings. The bolts e pass through the inner 60 ends of both the short arms D, the long arms D', and the castings. The eyebolts e' encircle the rods and pass through the castings and long arms. The bolts e'' pass through the rods c, 65 castings E, and short arms D. The castings are supplied at their inner ends with bearings d, and fitted to these are the guides F, said guides being provided with cam-grooves which fit the flange of the cam-plate G. Small blocks f are bolted to the outer portion of 70 these guides, the bolt-holes therein being so made that they can be adjusted to take up wear. These blocks also secure the guides to the above-mentioned flange when the reel is taken apart, thus preventing danger of 75 their loss. In these views the reel-head and cam-plate G are, for convenience, shown proportionately larger than I prefer to make them for use. Also the front of the cam-plate is shown somewhat higher. 80

It will readily be seen that the beater D'' (shown above the cam-plate in Fig. 1) will move about three times as fast in the first quarter of a revolution made by the reel as the one next before it. The reel-shaft should 85 revolve about thirty-three per cent. faster than for an ordinary reel, as by tilting it back the practical working speed of the reel will still be less than in other reels, while by tilting it ahead its practical working speed can be 90 doubled. At the same time the beaters always leave the grain slower than in other reels.

It will be seen that when the eccentric is raised or lowered the relative positions of its 95 front and rear sides are not changed, or, in other words, it is movable vertically without tilt.

I do not claim, broadly, the reel-arms pivoted to radial arms on a reel-shaft and 100 guided throughout their revolution by a cam-plate with a flange, as a patent has already been granted to me on a reel embracing the said construction, wherein the change of

movement was gained by using an irregularly-curved cam-plate with a cam-groove and guides consisting of rollers running therein, the cam-plate not being movable to front and rear. The present construction has the following advantages: The reel-arms have a steady even movement, given by the circular flange. As will be seen, so long as the guides are moving from the reel-shaft the outer ends of the reel-arms have an accelerated movement which gradually changes to a slow movement as the guides begin to move back toward the reel-shaft. This gradual change of motion can be fully attained only by the cam-plate being a circular eccentric. Then the practical increase of the working speed of the reel can only be effected by tilting the front of the eccentric downward, and by mounting said eccentric on an upright standard which can be tilted to front and rear the operator in moving the reel ahead is enabled to also increase its practical working speed by the same movement. The bearings of the guides are also held much more firmly in place by securing them directly to the pivotal bearings of the radial arms, and, lastly, by having the guides held in position by a single flange of the eccentric a greater variation of speed can be obtained and a smaller eccentric can be used, thus making the reel lighter, cheaper to build, and more effective.

I claim as my invention—

1. In a harvesting-machine, an upright standard hinged at its lower part to the frame of the machine, a sleeve-frame vertically movable thereon, an eccentric with a flange secured to said sleeve-frame, a reel-shaft passing through said eccentric at a point distant from its center and having bearing in the sleeve-frame, radial arms secured to said reel-shaft, bearing-plates and reel-arms rigidly secured together and pivoted to the radial arms, beaters rigidly secured to the outer ends of said reel-arms, and guides pivoted to the inner ends of said bearing-plates, said guides being secured in movable engagement with said eccentric.

2. In a harvesting-machine, an upright standard hinged at its lower part to the frame of the machine, a sleeve-frame vertically movable thereon, an eccentric plate with a flange secured to said sleeve-frame, a reel-shaft passing through said eccentric plate at a point distant from its center, radial arms secured to said reel-shaft, bearing-plates pivoted directly to said radial arms, guides pivoted to the inner ends of said bearing-plates and having bearing on the inside of said flange, and reel-arms secured to said bearing-plates.

3. In a harvester-reel, an eccentric plate with an annular flange, a reel-shaft passing through said eccentric plate at a point distant from its center, radial arms secured to said reel-shaft, bearing-plates and reel-arms rig-

idly secured together and pivoted to said radial arms, and guides pivoted to the inner ends of said bearing-plates, said guides having bearing on both the inside and outside of said flange. 65

4. In a harvesting-machine, an eccentric with a flange, a reel-shaft passing through said eccentric at a point distant from its center, radial arms secured to said reel-shaft, bearing-plates and reel-arms rigidly secured together and pivoted to said radial arms, 70 each and every one of said reel-arms being held by a bolt passing through it and through a bearing-plate, and guides pivoted to the inner ends of said bearing-plates, said guides being secured in movable contact with said flange. 75

5. In a harvesting-machine, an eccentric plate with a flange, a reel-shaft passing through said plate at a point distant from its center, radial arms secured to said reel-shaft, bearing-plates pivoted to said radial arms, guides pivoted to the inner ends of said bearing-plates, 80 said guides being held in movable engagement with said flange by means independent of said bearing-plates. 85

6. In a harvester-reel, an eccentric flanged plate movable vertically without tilt, a reel-shaft passing through said plate at a point distant from its center, radial arms secured to said reel-shaft, bearing-plates pivoted to 90 said radial arms, guides pivoted to the inner ends of said bearing-plates, said guides being secured in constant movable engagement with said flange. 95

7. In a harvester-reel, an eccentric flanged plate, a reel-shaft passing through said plate at a point distant from its center, radial arms secured to said reel-shaft, bearing-plates and reel-arms rigidly secured together and pivoted to said radial arms, and guides pivoted to the inner ends of said bearing-plates, 100 said guides being secured in sliding engagement with said flange. 105

8. In a harvesting-machine the combination of bearing-plates, radial arms on the reel-shaft to which said plates are pivoted, said plates supplied with bearing-pins at their inner ends, and reel-arms supporting the outer ends of the beaters, said reel-arms resting directly on the bearing-plates with an eccentric plate, an upright supporting-frame to the upper end of which said plate is adjustably fitted and rigidly secured and in which the reel-shaft has bearing and which is adjustable at its upper part to front and rear, and 110 guides pivoted to said bearing-plates and having bearing within a flange of said eccentric plate. 115
